UNITED STATES PATENT OFFICE.

GEORGE W. WEIDNER, OF CADILLAC, MICHIGAN.

ENGINE.

1,171,572.

Specification of Letters Patent. Patented Feb. 15, 1916.

Application filed June 14, 1915. Serial No. 34,110.

To all whom it may concern:

Be it known that I, GEORGE W. WEIDNER, a citizen of the United States, residing at Cadillac, in the county of Wexford and 5 State of Michigan, have invented a new and useful Engine, of which the following is a specification.

The present invention appertains to engines, and aims to provide a novel and improved engine operated by any suitable expansion or pressure fluid.

It is the object of the invention to provide an engine of such construction and operation, that the engine will not only 10 operate in an efficient and desirable manner, but will also operate without the usual pounding, jarring and vibrations incident in the operation of an ordinary engine, the present engine being balanced so as to operate smoothly and with little thrust against 15 the supporting frame.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 20 within the scope of what is claimed without departing from the spirit of the invention.

The invention is illustrated in the accompanying drawings, wherein:

Figure 1 is a side elevation of the improved engine, portions being broken away. Figs. 2 and 3 are cross sectional views taken on the lines 2-2 and 3-3, respectively, of Fig. 1. Fig. 4 is a longitudinal section taken 40 on the line 4-4 of Fig. 1.

In carrying out the invention, there is provided a cylinder 1 of suitable length and diameter, and having crank casing 2 at one end in which the crank shaft 3 is journaled 45 for rotation, said crank shaft having an intermediate crank 4 and a pair of cranks 5 at the opposite sides of the crank 4. The cranks 4 and 5 project in opposite directions. The engine embodies a second cylinder 6 of suitable length and diameter alining with and spaced slightly from the cylinder 1, and an annular casting or coupling 7 is secured to the adjacent ends of the cylinders for spacing them apart and rigidly 50 connecting them. The casting 7 has the

opening 8. A piston 9 is mounted for reciprocation within the cylinder 1 adjacent the crank case 2 and is connected by a connecting rod or piston 10 with the crank 4. A second piston 11 is mounted for reciprocation within the cylinder 1 remote from the crank case 2. The cylinder 6 also has a pair of pistons 12 and 13 mounted for reciprocation therein and movable toward and away from one another during the 65 operation of the engine.

The pistons 11 and 12 of the two cylinders are connected by a piston rod 14 which is terminally secured to the said pistons, and a cross head or yoke 15 has its intermediate 70 portion secured to the intermediate portion of the rod 14 and projects through the opening 8 of the casting 7. Stems 16 are secured to the ends of the cross head or yoke 15 and project toward the crank case 75 2, and the free ends of the stems 16 are provided with cross heads 17 working in longitudinal guides 18 provided upon diametrically opposite portions of the cylinder 1 adjacent that end of the cylinder remote 80 from the crank case. Connecting rods or pitmen 19 have their ends pivoted to the cross heads 17 and cranks 5. The pistons 11 and 12 being connected will be operated simultaneously in the same direction, and the pistons 9 and 13 are also connected to operate simultaneously in the same direction. 85

The piston 9 is provided with diametrically opposite outstanding arms 20 working in longitudinal slots 21 provided in opposite sides of the cylinder 1 adjacent the crank case 2, and longitudinal rods 22 each have one end secured to one of the arms 20. The rods 22 are located at opposite sides of 90 the cylinders and project away from the crank case beyond the remote end of the cylinder 6. The rods 22 are slideable through apertured guide ears 23 outstanding from that end of the cylinder 1 remote from the crank case, and through apertured guide ears 24 outstanding from the remote end of the cylinder 6. Those ends of the rods 22 remote from the crank case are connected 95 by a yoke 25 to which one end of a piston rod 26 is secured, the other end of said piston rod being attached to the piston 13. The rods 22 thus connect the pistons 9 and 13 whereby they move in the same direction. 100 Each of the cylinders is provided with in- 105

let and outlet ports 27 between its ends and between the pistons.

When the engine is employed as an internal combustion engine, suitable ignition means or spark plugs are provided for the cylinders between the pistons, and suitable valve gears are also employed, which need not be illustrated or described in detail.

The pistons in each cylinder move toward and away from one another, so that when an explosion occurs in one cylinder, the pistons will be separated therein, while the pistons of the other cylinder will be moved toward one another for compressing the new charge. Assuming that the parts are in the position illustrated in Fig. 4, when the explosion occurs in the cylinder 1, the pistons 9 and 11 will be separated, and the piston rod 10 will force the crank 4 away from the cylinder 1, while the yoke 15 being forced away from the crank case by the piston 11 will cause the pitmen 19 to pull the cranks 5 toward the cylinder 1. In this manner, the thrust created by the explosion will be neutralized or balanced, to minimize the jarring or vibration. Since the pistons 12 and 13 are moved in the same direction as the pistons 11 and 9, respectively, when the pistons 9 and 11 are separated, the pistons 12 and 13 will be moved toward one another for compressing the new charge within the cylinder 6. Then when the charge within the cylinder 6 is exploded, the pistons 12 and 13 will separate, while the pistons 9 and 11 will be forced toward one another for ejecting the burnt gases from the cylinder 1, and then when the pistons 9 and 11 separate, the new charge will be drawn into the cylinder 1, while the burnt charge will be ejected from the cylinder 6.

The engine may also utilize steam or other pressure fluid as a driving medium, and with the same advantages as with the

use of gasoline or other similar fuel. The 45 guides 18 may be eliminated by guiding the yoke 15 within the casting 7, if desired. Likewise, any other changes in details may be resorted to, within the scope of what is claimed, in constructing the engine, as may 50 be found essential, without departing from the spirit of the invention.

Having thus described the invention, what is claimed as new is:

An engine embodying a pair of alining 55 cylinders, one having a crank case at that end remote from the other cylinder, a crank shaft journaled for rotation within the crank case and having a pair of cranks and an intermediate crank projecting in opposite directions, a pair of pistons working within each cylinder, a member disposed between and secured to the adjacent ends of the cylinders and having an opening, a piston rod connecting the adjacent pistons of 65 the two cylinders, a yoke secured to said piston rod and working in said opening, connecting rods connecting said yoke and said pair of cranks, a connecting rod connecting the intermediate crank and that piston adjacent the crank case, the first mentioned cylinder having longitudinal slots 70 adjacent the crank case and the last mentioned piston having outstanding arms working in said slots, longitudinal rods attached to said arms, the cylinders having guides for the last mentioned rods, a yoke secured to the last mentioned rods remote from the crank case, and a piston rod connecting the last mentioned yoke and that 80 piston remote from the crank case.

In testimony that I claim the foregoing as my own, I have hereto affixed my signature in the presence of two witnesses.

GEORGE W. WEIDNER.
